UNITED STATES PATENT OFFICE.

WALTER EVERETT MOLINS, OF DEPTFORD, LONDON, ENGLAND.

MECHANISM FOR SEVERING MOVING WEBS INTO LENGTHS.

Application filed January 22, 1927, Serial No. 162,910, and in Great Britain January 22, 1926.

This invention is for improvements in or relating to a device for severing a moving web into lengths and more particularly to a device wherein the cutting mechanism comprises a fixed blade adapted to co-operate with a rotary blade, and it is the object of the present invention to provide on such a device means whereby the leading edge of the severed web is simultaneously deflected 5 from both the fixed and rotary blades in its path through the machine.

The present invention consists of a device for severing a travelling web of paper or the like, into lengths which comprises in combination a fixed cutting blade a rotary cutting blade, means adapted to deflect the leading edge of the freshly cut web out of the path of the fixed blade and an air current adapted to deflect the leading edge of the 20 web out of the path of the rotary blade.

The invention is more particularly described with reference to the accompanying drawing which illustrates one method of carrying the invention into effect wherein:—

25 Fig. 1 is a section of the cutting device, and

Fig. 2 shows the parts in a different position.

Referring to the drawing which illustrates 30 a cutting mechanism constructed according to British patent specification No. 245,261, wherein a resilient deflector 1 is arranged to operate in conjunction with the fixed blade 2 in the manner described in British patent specification No. 245,261 to remove the leading edge of the freshly cut web out of the path of the fixed blade 2. It is found in practice that when the leading edge of the web has been deflected from the fixed blade there 35 is a tendency for the same to be attracted by the rotary blade 3 and adhere to the same, thereby rendering the delivery of the various strips to a stacking mechanism extremely difficult.

40 In the deflector described in my British patent specification No. 245,261, the deflector is mounted so as to be directed towards the cutting edge of the fixed blade 2 in such a manner that the free end of the deflector 1 is located in the path of the rotary blade.

45 According to one construction of the pres-

ent invention the deflector associated with the rotary cutting blade comprises a pneumatic device 4 adapted to produce an upwardly directed air blast indicated by the 55 numeral 5 and adapted to issue from the nozzle 6 of the device 4 in a line joining the nozzle 6 with the free end of the deflector 1.

It is found in practice that as the web is being fed through the machine the air blast 60 5 associated with the rotary blade 3 is deflected by the surface 7 of the rotary cutting blade on to the travelling web 8 and the inclination of the air blast varies as the rotary cutting blade moves towards the fixed blade. 65 After the web has been severed the air blast supports the leading edge of the web and peels it from the edge of the rotary blade.

The force of the air blast is sufficient to 70 destroy any tendency for the web to adhere to the rotary blade, and also acts as a support which, in the case of a freshly printed surface, prevents any tendency to smear.

In addition to the oblique blast there may 75 be provided air nozzles 9 and 10 on either side of the cutting mechanism which permit an upwardly directed blast of air to support the web in its forward movement, and thereafter support the strips in their path towards the stacking mechanism so as to ensure 80 that the printed strip does not come in contact with any surface which might smudge the same.

What I claim as my invention and desire 85 to secure by Letters Patent is:—

1. A device for severing a travelling web of paper or the like into lengths, which comprises in combination a fixed cutting blade, a rotary cutting blade, means adapted to deflect the leading edge of the freshly cut 90 web out of a path which includes the fixed blade and an air current adapted to deflect the leading edge of the web out of the path of the rotary blade.

2. A device for severing a travelling web 95 of paper or the like into lengths which comprises in combination a fixed cutting blade, a rotary cutting blade, a resilient deflector inclined to the plane of the fixed blade in such a manner that the leading edge thereof is 100 located in close proximity to the edge of the fixed blade and in the path of the rotary

blade in such a manner as to deflect the leading edge of the freshly cut web out of a path which includes the fixed blade and an air current adapted to issue in the direction of movement of the rotary blade, but directed away from the axis of the rotary blade and towards the free end of the deflector of

the fixed blade in such a manner as to deflect the leading edge of the freshly cut web away from the edge of the rotary blade. 10

In testimony whereof I hereunto affix my signature.

WALTER EVERETT MOLINS.
